UNITED STATES PATENT OFFICE

123,647

DESIGN FOR CHESS PIECES

Shepard J. Goldin, Washington, D. C.

Original application January 5, 1940, Serial No. 89,308. Divided and this application August 22, 1940, Serial No. 94,572

Term of patent 14 years

To all whom it may concern:

Be it known that I, Shepard J. Goldin, a citizen of the United States of America, residing at 705 18th St. N. W., Washington, in the District of Columbia, have invented a new, original, and ornamental Design for Chess Pieces, of which the following is a specification, reference being had to the accompanying drawing, forming part thereof.

This application is a division of application Ser. No. D-89,308, filed Jan. 5, 1940.

Figure 1 shows plan view of the chess pieces embodying my new design.

Figure 2 shows an edge elevational view of one of the chess pieces disclosed by Figure 1.

I claim:

The ornamental design for chess pieces, substantially as shown.

SHEPARD J. GOLDIN.
